UNITED STATES PATENT OFFICE.

WASHINGTON FLETCHER NICHOLS, OF MUNFORDVILLE, KENTUCKY.

MAGNETIC TYPEWRITING MACHINE.

Application filed September 5, 1922. Serial No. 586,148.

To all whom it may concern:

Be it known that I, WASHINGTON FLETCHER NICHOLS, a citizen of the United States, residing at Munfordville, in the county of Hart, State of Kentucky, have invented new and useful Improvements in Magnetic Type-writing Machines, of which the following is a specification.

This invention relates to improvements in typewriting machines and more particularly to key bars, type bars and intermediate or magnet bars, together with electrical connections associated with said key, type and magnet bars, in which an electric current 10 from a battery or other electrogenerating device is so conducted that when a key bar of said machine is depressed a closed circuit is formed resulting in the magnetizing of an electromagnet mounted on the end of an intermediate or magnet bar which in turn is 20 attracted to an adjacent soft iron, or control bar and by means of a connecting pitman attached to the distal end of a type bar actuates said type bar causing the proximal end or type end to ascend thru an arc to a platen above in the ordinary manner of type bars when actuated by finger pressure.

The objects of the improvement are, first, to provide a typewriting machine in which 30 the type bars are actuated by electro-magnetic force, thus relieving much of the stress of long hours of typing by finger force; second, to provide a typewriting machine in which intermediate or magnet bars are actuated by electromagnets mounted on the ends of said magnet bars, and which are connected by pitmen to the distal end of the type bars causing them to ascend to the platen as the magnet bar descends; third, to 40 provide an open electric circuit which becomes a closed circuit as each successive key bar is pressed to contact point provided below causing current from the battery or other electric generating device to pass thru 50 said key bar, thence from contact point thru insulated wires to an electromagnet mounted on the end of the magnet bar; fourth, to provide means by which said insulated conducting wires from contact points of key 55 bars may be readily connected to any of the wires leading to the magnet coils on the ends of the magnet bars; as, for example, connecting the wire from the "A" key bar to the magnet on the end of the "N" magnet bar and vice versa. By this means illegible articles or cryptic messages may be written

at the ordinary speed of the typist and after delivery may be as readily transposed or translated by means of another similar machine in which the same changes of electrical 60 connections have been made as in the original machine; fifth, to provide an electro-magnetic complex together with key bars, magnet bars and type bars and such other modifications as are necessary to carry out 65 the spirit of this invention, which may be adopted or applied to existing typewriting machines or embodied in an entirely new machine.

While the principles of this invention may 70 assume a number of mechanical variations, one form of the invention is illustrated in the accompanying drawing.

The figure of the drawing represents a cross section of a typewriting machine looking from the right side of the machine toward the left. The improvements proposed for the machine and for which Letters Patent are prayed in my petition are represented by the heavier unbroken lines 75 and shadings of said drawings and shadings, the lighter dotted lines representing such outlines of the machine as are necessary to show the relations of said improvements to the whole machine.

A represents a full side view of a key bar; B represents a cross section of a soft iron control bar; C represents a full side view of a magnet bar; D represents a side view of a pitman between magnet bars and type bars; 80 E represents a side view of a type bar; F represents an end view of the platen but for which no claim for improvement is made; G represents a longitudinal section thru an L-shaped wire terminal and contact point 85 for key bar; H represents a spiral spring by which key bars are returned to place; and J represents the spring to a magnet bar, all parts of which are described in detail and function of each part and of the 90 whole set forth as follows:

A represents a key bar composed of a good conductor of electricity in which 1 is an ordinary typewriter key, bearing on its upper visible face its respective letter or 105 other character and mounted on the key bar by hard rubber or some other insulating material; 2 is a contact point on said key bar by which electrical contact is made with 5 by pressing down the key bar; 4 represents 110 a cross section or end view of a small, cylindrical steel shaft upon which all the key

bars are mounted so as to freely rotate thereon and make good electrical contact, but which shaft is insulated from the rest of the machine by hard rubber or other good insulating material; B represents a cross sectional end view of a soft iron bar or control bar extending across the machine from the right to the left and curved in such a manner as to form an arc parallel to the type bar rest above and serving as an attraction to magnets on magnet bars above; C represents a small, strong bar of aluminum or other non-magnetic substance known as the magnet bar mounted similarly to the key bars except that the magnet bars need not be insulated; upon the end of each magnet bar is mounted an electro-magnet 14, which consists of a soft iron core wound by a sufficient amount of small copper wire to produce the necessary magnetic force for its purpose; the magnetic field of these electromagnets must be well within the magnetic field of the soft iron bar, B; D represents a pitman or small steel connecting bar connecting magnet bar to corresponding type bar E, in such a way as to produce a constantly accelerating motion of the type bar as it ascends; 15 and 16 represent the small pins by which the pitman is connected to the magnet bar and the type bar; E represents a type bar not very different from the ordinary type bars, but made of some non-magnetic material and provided with above described connections thru pitman D, with the magnet bar adjacent and pivoted at 17, so as to be freely movable by said pitman D, above described, and having on its proximal end the ordinary type found on type bars, 18; these type bars when at rest return to their common type bar rest, 19, which consists of a curved, plush covered rest made of non-magnetic material; F represents an ordinary typewriter platen; G represents a longitudinal sections thru the L-shaped, insulating terminal with which the contact point 2, of key bar A is brought in contact by depressing the key 1. This connection is made of a good conducting material and has a slip-in mortise for the connecting plug or tenon on the proximal end of wire 8, and is embedded in insulating material separating the several connections from each other and from the rest of the machine; H represents a small coiled spring by which the key bar is returned after each depression; this spring must be insulated from the rest of the machine; J represents a similar spring to magnet bar to return and with it the type bar after the circuit is broken; 8 represents an insulated copper wire or connecting cord from the terminal G, to the terminal 10 where it is connected by a small slip-in tenon or other convenient means to the double contact terminal from which the wire 11-12

carries the current to magnet coil 14. These wires or cords must be sufficient to reach from their own connections at G to any one of the magnet bar terminals, 10 and 11. Connections, 10 and 11 like connection G, before described, must be fully insulated from each other and from the rest of the machine.

12 represents the insulated wire from connection 11 to the magnet coil, 14; 21 represents the return wire from the coil 14 to the common ground connection at 23; ground connection 23 is insulated from the rest of the machine but not from each other. 24 represents a common return wire from the common ground 23 to the battery; 20 represents the direct wire from the battery or other generating device to the key bar shaft 4.

All parts of the typewriting machine not herein described remain essentially as they are now found in existing machines, except such modifications as are necessary to carry out the principles of this invention.

The operation of a typewriter in which these improvements are embodied may be described as follows:

Current from the battery or other generating device passes up thru wire 20 to shaft 4, thence from shaft 4 thru each individual key bar A and when said key bar is depressed to contact at 2-5, thence thru terminal G, thence thru wire 8 to connection 10, thence thru connection 11 and wire 12 to magnet coil 14, thence thru the windings of coil 14, forming an electromagnet of the core of said coil 14, thence by return by wire 21, to common ground connection 23 and finally returned by wire 24.

When coil 14 is charged and an electromagnet is formed of its core, it is attracted to fixed soft iron bar B, which is well within magnetic range of said magnets, thus actuating type bar E thru pitman D before described.

In this invention I claim:

1. In a typewriting machine, in combination type bars, a movable magnet bar for each type bar and operatively connected to a type bar to actuate same, a magnet carried by each magnet bar, a control bar spaced from and located within the field of said magnet to cause attraction thereof when a magnet is energized, means to energize any desired magnet.

2. In a typewriting machine, in combination type bars, a movable magnet bar for each type bar, a pitman operatively connecting a type bar with a magnet bar, a magnet carried by each magnet bar, a control bar spaced from and located within the field of said magnet to cause attraction thereof when a magnet is energized, means to energize any desired magnet.

3. In a typewriting machine, in combina-

- tion type bars, a movable magnet bar for each type bar, a pitman operatively connecting each type bar with a magnet bar, a magnet carried by each magnet bar, a control bar spaced from and within the field of said magnet to cause attraction thereof when a magnet is energized, a key lever for each type bar and magnet bar provided with a contact point by means of which a closed circuit may be formed to energize a magnet on any desired magnet bar.
4. In a typewriting machine, in combination type bars arranged laterally in an arc, a movable magnet bar for each type bar arranged in a similar arc, a pitman operatively connecting each type bar with a magnet bar, a magnet carried by each magnet bar arranged also in an arc corresponding to the magnet bars, a soft iron control bar forming an arc laterally corresponding to the arc formed by the magnet bars and magnets and spaced from and within the field of said magnets to cause attraction thereof when a magnet is energized, a key lever for each type bar and magnet bar provided with a contact point by means of which a closed circuit may be formed to energize a magnet on any desired magnet bar, means to energize said magnet through a key bar when depressed.
5. In a typewriting machine, in combination type bars, a movable magnet bar for each type bar and operatively connected to a type bar by a pitman to actuate same, a magnet carried by each magnet bar, a control bar spaced from and located within the field of said magnet to cause attraction thereof when a magnet is energized, key levers bearing the characters on their upper surfaces and provided with contact points on their lower surfaces for forming a closed circuit to any desired magnet, an insulated wire from each contact point of a key lever to a connecting point of a similar wire to a magnet and so constructed as to be readily connected to any desired magnet, an insulated wire to the winding of each magnet, a similar return wire from each magnet to a common return wire connection, an insulated metallic return wire connection which is provided with ready means of attaching the return wires from the magnets and the common return or ground wire, a key lever shaft which is insulated from the body of the machine but makes contact with the key levers which are mounted on it and which is provided with ready attachment of the wire from the battery or such E. M. F. as may be used.
6. A device in typewriting machines consisting of key bars, magnet bars, magnets, pitmen, soft iron control bar, type bars and type bar rest as described, also an electromagnetic complex by which said device is to be operated and consisting of (1) an insulated wire or cord from the battery or other electrogenerating device to the key bar shaft to which it is connected by a slip-in plug or some other convenient method, (2) the key bar shaft and key bars as before described (3) the wire from the key bar contact point to the magnet bar wire terminal to which it is connected by a slip-in plug or such convenient means (4) the magnet bar wire to the coil on the end of the magnet bar (5) the electromagnet above named (6) a return wire from coils to common ground connection, and (7) a wire from common ground connection back to battery or other generating device, all wires should be flexible, insulated and have an easy and efficient method of connection, as a slip-in plug or tenon, at each end so as to be readily renewed or changed.
